Primary Examiner — Patricia A Palasik(74) *Attorney, Agent, or Firm* — Crowell & Moring LLP(57) **CLAIM**

The ornamental design for a mobile job site robot, as shown and described.

DESCRIPTION

FIG. 1 is a perspective view of a mobile jobsite robot according to the design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken lines in the drawings depict portions of the mobile jobsite robot which form no part of the claimed design.
